CENTRIFUGAL UNLOADER FOR
COMPRESSORS

Ellis Nathan, Easton, Pa., assignor to Pennsylvania Pump & Compressor Company, Easton, Pa., a corporation of Pennsylvania

Application June 29, 1946, Serial No. 680,501

3 Claims. (Cl. 230—29)

1

This invention relates to compressors for air and gasses and particularly to a starting unloader for a motor driven compressor.

An object of the invention is to provide an improved centrifugally operated valve adapted to be moved from its unloading position to its loading position when the motor and compressor reach a predetermined speed of rotation.

A feature that enables the above object to be accomplished is that the valve itself is weighted and is normally held by a spring in an unloading position while the compressor is at rest or coming up to speed, the valve being movable to its loading position against the pressure of the spring as soon as the compressor reaches a predetermined speed of rotation.

Another object of the invention is to provide a compact rotating valve body driven by the compressor motor, the valve body being continuously connected to the receiver and to the unloading devices by suitable conduits during its rotation.

In motor driven compressors it is desirable to start the motor, while pressure is in the receiver, with the compressor unloaded so that an extremely heavy load will not be applied to the motor when starting. As soon as the motor has acquired normal speed the compressor can be loaded without overloading the motor. It is to provide a convenient valve mechanism for maintaining the compressor unloaded until the motor acquires normal rotative speed and then to load the compressor that the present mechanism has been developed.

Other objects and advantages will be apparent from the specification and claims, and from the drawing which illustrates what is now considered to be a preferred embodiment of the invention.

In the drawings:

Figure 1 is a side elevation of a complete motor driven compressor installation having the present invention applied thereto, and

Fig. 2 is a sectional view of the rotatable centrifugal valve forming the present invention.

In its preferred form the invention may include the following principal parts: First, a compressor cylinder; second, a receiver connected thereto; third, unloader valves preferably controlling the intake valves of the compressor; fourth, a motor drivingly connected to the compressor; fifth, a rotatable valve body having a spool valve therein normally held in one position and having a weighted end; and sixth, conduits leading to ports in the valve body opened and closed by movements of the valve, the conduits being connected

2

to the compressor receiver and to the unloading devices.

Referring more in detail to the figures of the drawing, there is shown at 10 a compressor of standard or conventional double-acting type having an intake at 12 and a discharge at 14 connected to any form of receiver 16. Intake and discharge valves (not shown) are provided at opposite ends of the cylinder, the intake valves 10 being movable to positions to load or unload the compressor by suitable devices 18 which may be similar to those shown and described in the patent to Merwarth granted December 31, 1929, No. 1,741,426.

15 The compressor as shown is operated by an electric motor 20 connected directly to the main crank shaft 22 of the compressor. The circuit and starting equipment for the motor 20 are not shown and may be of any usual standard type.

20 Starting the compressor without appreciable pressure within the receiver 16 does not overburden the motor 20, but with discharge pressure within the receiver 16 the compressor 10 should be allowed to operate idly without compressing any air or gas until the motor 20 is running at approximately normal speed.

25 Driven from the main crank shaft 22 of the compressor, as by means of a belt 24, is a rotatable valve body 26. As shown, the valve body 26 may be supported upon a suitable bracket 28. On the valve body 26 is a pulley 30 formed thereon over which the belt 24 rides. To rotatably support the valve body 26 an anti-friction bearing 32 may be employed at one end. The body 26 is 30 also supported by engagement of its opposite end with a connection block 34 spring pressed in one direction by a suitable spring 36. Spring 36 surrounds a nut 35 threaded to a bolt 37 supported in the bracket 28. The inner end of bolt 37 is squared and fits within a suitable recess formed in the connection block 34.

35 The connection block 34 is coupled to pipes 38 and 40, pipe 38 extending to the valve unloaders 18 and pipe 40 extending to the receiver 16.

40 Pipes 38 and 40 connect in the block 34 with ports within the revolving valve body in a manner so that pipe 38 connects with the cylinder for an unloader valve 42 at ports 44 and 46 and pipe 40 at port 48. The valve 42 has a heavily 45 weighted end and two neck portions so that three heads are formed closely fitting the cylinder as shown. The connection between pipes 38 and 40 and the ports 44 and 48 is maintained substantially pressure tight by means of the spring 50. A spring 50 normally holds the valve 42 in

the position shown while the compressor is at rest and until it acquires substantially normal speed. In this position of the valve 42 when the compressor is not running or is coming up to speed pipe 40 is connected at port 48 to the valve cylinder and pressure from receiver 16 may pass the neck of valve 42 to port 44 and through the conduit 39 to pipe 38 and thence to the unloaders 18. The motor will therefore not be heavily loaded. As soon as the compressor motor 20 reaches substantially normal speed the valve 42 moves radially outward from the axis of rotation of the valve body 26 against the pressure of spring 50. This moves the weighted end of the valve 42 far enough to uncover port 52 so that the pressure acting on the unloader 18 supplied through pipe 38 may exhaust to atmosphere. Simultaneously, the head at the opposite or small end of the valve 42 moves to close port 48 and prevent pressure from the receiver 16 reaching the valve cylinder through pipe 40. This movement of the valve 42 also moves the intermediate head to uncover conduit 39 at the same time it closes port 48.

As soon as pressure in conduit 38 has been released by opening pipe 38 and conduit 39 to atmosphere, the unloaders 18 are rendered inoperative and the intake valves of the compressor can function normally.

It will be understood that unloader devices 18 may also be controlled to unload the compressor when the maximum discharge pressure is reached in the receiver 16. The centrifugal valve 42, however, is employed only for maintaining the compressor unloaded during starting of the motor 20. To vary the speed at which the valve 42 will move to its operative or loading position, it is only necessary to vary the pressure exerted by spring 50. This may be done by adjustment of screw 54 bearing against the outer end of spring 50.

I claim as my invention:

1. A centrifugal starting unloader for a motor driven compressor comprising a rotatable valve body driven by the compressor motor, a receiver for said compressor, unloading devices therefor, conduits from the compressor receiver and to said compressor unloader devices communicating with said valve body, and a valve within said body controlling said conduits, said valve being spring pressed in a direction to normally admit discharge pressure to said compressor unloading devices, and said valve being movable, when said compressor is operating at substantially normal speed, to a position to exhaust pressure from said

unloading devices to atmosphere and permit normal operation of the compressor.

2. A centrifugal starting unloader for a motor driven compressor comprising a rotatable valve body driven by said compressor motor, a receiver for said compressor, unloading devices therefor, separate conduits connecting said valve body with the compressor receiver and with said compressor unloading devices, a valve movable within said rotatable body and normally held in a position to connect pressure within said receiver with said unloader devices, said valve being moved when said compressor is operating at normal speed to a position cutting off pressure from said receiver to said unloading devices and connecting said unloading devices to atmosphere to permit normal operation of the compressor.

3. A centrifugal loading valve for a motor driven compressor comprising a rotating valve body driven by said compressor motor, a receiver for said compressor, unloading devices therefor, conduits connecting said body to said receiver and to said unloading devices for said compressor, a connection block for said conduits, and resilient means to maintain said connection block in contact with an end face of said valve body, a spool valve rotatable with and movable radially of said valve body, said valve in one position connecting said receiver and unloading devices, and in another position cutting off receiver pressure from said unloading devices and connecting said unloading devices to atmosphere, a spring normally retaining said valve in position to maintain pressure within said unloader devices, said valve being weighted at one end whereby at a predetermined speed of said compressor said valve will be moved against the pressure of said spring to close the conduit from the receiver and exhaust receiver pressure from said unloader devices to atmosphere and permit normal operation of said compressor.

ELLIS NATHAN.
